UNITED STATES PATENT OFFICE.

JACOB MUNTENER, OF NEEDHAM HEIGHTS, MASSACHUSETTS, ASSIGNOR TO DOLGEVILLE FELT SHOE COMPANY, OF DOLGEVILLE, NEW YORK, A CORPORATION OF NEW YORK.

DESIGN FOR A SLIPPER.

Application filed February 27, 1924. Serial No. 8,788. Term of patent 7 years.

To all whom it may concern:

Be it known that I, JACOB MUNTENER, a citizen of the United States, residing at Needham Heights, county of Norfolk and State of Massachusetts, have invented a new, original, and ornamental Design for a Slipper, of which the following is a specification, reference being had to the accompanying drawing, forming part thereof, wherein the figure is a perspective view of a slipper showing my new design.

I claim:

The ornamental design for a slipper as shown.

Signed at West Hoboken, in the county of Hudson, and State of New Jersey, this 25th day of February, 1924.

JACOB MUNTENER.
